UNITED STATES PATENT OFFICE.

THOMAS J. LEVEY, OF BALTIMORE, MARYLAND, ASSIGNOR, BY MESNE ASSIGNMENTS, TO FERDINAND GUTMANN & COMPANY, OF NEW YORK, N. Y., A CORPORATION OF NEW YORK.

CAPPING-MACHINE FOR BOTTLES.

1,333,025.

Specification of Letters Patent.

Patented Mar. 9, 1920.

Original application filed January 30, 1917, Serial No. 145,492. Divided and this application filed July 23, 1917. Serial No. 182,282.

To all whom it may concern:

Be it known that I, THOMAS J. LEVEY, a citizen of the United States, residing at Baltimore, in the State of Maryland, have invented certain new and useful Improvements in Capping-Machines for Bottles; and I do hereby declare the following to be a full, clear, and exact description of the invention, such as will enable others skilled in the art to which it appertains to make and use the same.

This invention relates to bottle capping machines and has for its object to provide a machine of this nature which will be comparatively inexpensive to manufacture, certain in action and more efficient in use than those heretofore proposed.

With these and other objects in view the invention consists in the novel details of construction and combinations of parts more fully hereinafter described and particularly pointed out in the claim.

This application is a division of my pending application Serial No. 145,492, filed January 30, 1917, entitled Bottle capping machine.

Referring to the accompanying drawings, forming a part of this specification, in which like numerals designate like parts in all the views;

Figure 1 is an elevational view partly in section of a machine made in accordance with this invention;

Fig. 2 is a sectional elevational view of a portion of the parts shown in Fig. 1;

Fig. 3 is a sectional detail view taken on the line 3—3 of Fig. 1 looking in the direction of the arrows;

Fig. 4 is a detail view partly in section of the operating cam and its associated parts illustrated in Fig. 1;

Fig. 5 is a bottom plan view of the driven fingers or rollers illustrated in Fig. 4; and

Fig. 6 is a sectional elevational view taken on the line 6—6 of Fig. 1, showing the construction of the intermittent clutch mechanism.

1 indicates any suitable source of power for example, an electric motor mounted on the bracket 2 and having the driving shaft 3 adapted to impart motion to the driving belt 4 which, through mechanism not illustrated, drives the power shaft 5 carrying the

drive pulley 6 over which passes the power belt 7. Said power belt 7 also passes over the driving pulley 8, loosely mounted on the main drive shaft 9, provided with a clutch mechanism 10 adapted to connect and disconnect said pulley 8 with said shaft 9 when starting and stopping the machine. Rigid with said shaft 9 is an intermittent clutch member 11 provided with the tripping dogs 12, adapted to coact with the clutch lever 13, rigid with the sleeve 14, loose on the shaft 9, and carrying the driving pinion 15, all as will be clear from my prior Patent #974402, dated November 1, 1910, and entitled Power transmitting device. There are two clutches 11 and clutch levers 13 associated with corresponding driving pinions 15 and 16, as illustrated in Fig. 1, and they impart motion to a pair of vertically movable racks 17 and 18 respectively.

These said racks are respectively rigid with the reciprocating capping head operating rods 19 and 20, associated with their corresponding capping heads 25 and 65. As the said heads are duplicates of each other, only the one lettered 25 will be described in detail.

Referring more especially to Fig. 2, the capping head operating rod 19 is associated with an outer barrel 21 in which the said rod 19 reciprocates and the latter is surrounded by the compression spring 22 which is compressed when said rod is moved downwardly by the pinion 15, as seen in said Fig. 3; and said spring serves to return the parts into the position shown when said lever 13 is released in the manner to be disclosed below. Rigid with the upper portion of the rod 19 is the arm 23, which surrounds the tubular member 24, which is or may be associated with the capping head 25, the detail construction of which is or may be substantially the same as that disclosed in my former Patent #1160084, dated November 9, 1915, and entitled Bottle capping machines.

That is to say, mounted on the interior of the capping head 25 is a mechanism similar to that illustrated in said last mentioned patent which is adapted to crimp caps around bottle necks that are suitably presented to the lower end 66 thereof, as the said rod 19 and arm 23 move up and down, all in a manner well known,

Going back to the main driving shaft 9, it is provided with a spirally grooved cam 30 having an inclined portion 31 and a dwell portion 32 as shown. Coacting with said cam 30 is a plurality of driven rollers, fingers or teeth 33 mounted on the disk or flange 34, carried by the sleeve-like member 35 rigid with the tubular member 36, so that as said roller members 33 are revolved by said cam 30, the said tubular member 36 will be rotated on its center as an axis. The said tubular member 36 is supported by and is revolved in the main frame work 37 as shown, and is rigid with the annular bottle carrying table 38 provided with the pads or cushions 39 preferably made of rubber and having the cup shaped brass protecting plates 40 as illustrated. The said rigid table member 38 is provided with the tubular extension 42 inside which fits the hollow adjustable member 43 provided with a plurality of circularly disposed bores 44, and on the outside of said bores said cylindrical member 43 is provided with the annular flange 45. Said circularly disposed bores 44 surround a central space or bore 67, and the outer wall of said bore 67 is screw threaded on to the tubular member 46 which extends up to and receives the flange 38 of the spider member 49. Passing through said spider member 49 said flange 48 and said member 46, is the pin 50 provided with the enlarged collar 51 and the screw threaded lower portion 52 as shown. The said screw threaded lower portion 52 of the pin 50 takes into the upper portion 53 of the tubular member 36 and the upper portion of the rod 50 is suitably provided with a collar 54 to secure the parts firmly together.

Passing through the annular flange 45 is a plurality of vertical guide rods 55 passing through holes in the individual segments 56 of the cap carrying mechanism, as will be clear from Figs. 1 and 2. Each of these segments 56 is provided with a depression 57 adapted to receive a bottle cap (not shown) and each segment also fits over a nipple or stud 58 carried by the tubular plunger member 59 slidably mounted in its corresponding bore 44. Located in said tubular member 59 and bore 44 is a spiral spring 60, one for each segment 56.

Above the depressible cap carrying sectors 56 there is provided the stationary metal plate 76 provided with the orifice 504 to accommodate the capping head 25, which plate serves the purpose of preventing the caps from jumping out of the depressions or apertures 57 during the descent of the capping head 25 or during the rotating of the sectors 56. During the descent of the capping sectors 36, they are guided by the rods 55 mounted in the annular flange 45, and as will be clear from Fig. 4, the said sectors 56 may descend as far as the said

flange 45 should it be so desired. In other words, by adjusting the member 43 carrying the said flange 45, up and down, bottles of different heights may be readily accommodated. That is to say, the upper edge of the extension 42 accommodates an adjusting collar or sleeve 77, and the said sleeve may be readily removed and a sleeve of a wider or of a narrower dimension may be substituted, thus raising or lowering the flange 45, according to the height of the bottle being capped. In order to facilitate this adjustment of the flange 45 up and down, it is preferred to use split sleeves such as 77, see Fig. 1, and in order to facilitate the bodily movement of the said flange 45, a wrench may be applied to the upper end of the rod 50 whereupon the said rod through the screw threads 52 may be loosened up sufficiently to accommodate any predetermined size of collar 77, and then it may be screwed down so as to hold said collar firmly in place. In other words, it is a comparatively easy matter to interchange the collars 77 and to thus accommodate bottles of different dimensions without any material stoppage of the capping operation.

Of course, whenever the length of the bottle 100 is changed the beginning and end of the stroke of the bottle capping head must be likewise changed. In order to accomplish this purpose collars which may be split collars such as 78 and 79, see Fig. 1, are located on each side of the arms 23 and by properly choosing the dimensions of the said collars 78 and 79, the beginning and the end of the stroke of the capping head 23 may be located in any desirable positions.

Rising approximately on the center line of the machine, is a supporting post 200 and the bottle feeding tables and bottle capping mechanisms above mentioned are located symmetrically on both sides of said center line so that the bottle capping operations performed by the bottle capping heads 25 and 65 may alternate with each other and thus the capacity of the machine is substantially doubled.

The caps for the bottles are conveniently carried in the hopper 201 and they are fed from said hopper by the oscillating cap feeders 202 and 203 to the chutes 204 and 205 respectively. The said hopper and chutes are of any suitable or desired construction, such for example as that shown in my said Patent 1160084 and the parts are so arranged that bottle caps are presented to the various sectors 56 always with their cork side downward. The said chutes 204 and 205 deliver to the said sectors 56 at points about 135° from their respective bottle capping heads 25 and 65, as may be gathered from Fig. 1, but the particular point at which these chutes deliver their caps is a matter of small importance. As

the caps are delivered to their respective sectors, the intermittent rotation of the sectors in the manner above disclosed brings the said caps underneath the bottle capping heads. It should be observed that the said cap holding sectors 56 derive their motion from the inclined portion 31 of the grooves of the cams 30 and that the dwell portions 32 of the said cam grooves hold the said 5 sectors firmly in correct alinement with their respective capping heads during the capping operation. During the capping operation considerable strain is brought upon the tables such as 38 and 110 and in order to take 10 care of this strain, I preferably provide in the casting 37, directly beneath the capping heads, an adjustable member 210 provided with the screw threads 211 over which screw the adjustable nuts 212. The upper 15 end of said member 210 is bored as shown to receive the projection 213 of a table supporting disk 214 which fits up against the under side of the table 38, for example, and thus firmly supports the said tables 38 when 20 25 the capping head 25 is crimping the cap onto the head 72 of the bottle 100. Inside each of the tubular members 21 is located a spring 22 as above mentioned and in order to cushion the parts I provide on each of the 30 35 reciprocating rods 19 and 20 a piston like member 220, see Figs. 2 and 3. The said tubular members 21 are likewise bored out as at 222 to accommodate the reciprocations of said pistons 220. Accordingly, as the 35 40 said pistons 220 descend they readily expel the air inside the tubular members through the openings 223. As said pistons 220 descend more or less air passes through the passages 221 and the cocks 400, and when 40 45 said pistons 220 descend this said air becomes more or less trapped on the inside of said pistons owing to the automatic closure of the check valves 401. Accordingly, said trapped air slowly escapes through the partly closed cocks 400 as said pistons ascend, and thus the motion of the rods 19 and 20 is cushioned on their ascent by said 45 50 55 trapped air.

410 represents an opening for admitting air past the valve 401, and 411 indicates an oil cup for feeding oil with the air entering through the orifice 410. 412 represents a circumferential channel for the oil and air and 413 connections between said channel and the space above the piston 220.

Any suitable mechanism may be provided for controlling the clutch mechanism 10, but I have shown a crank 225 mounted on a stub shaft 226, carrying a crank arm 227, connected by a link 228 to a similar crank arm 229 carried by a rod or shaft 230, which is connected by a suitable link 231 to the clutch 10, all as will be clear from Fig. 1. It is therefore possible to start and stop the en-

tire machine by merely moving the crank 65 handle 225 from one position to another, the said movement serving to engage or disengage the pulley 8 from the main power shaft 9, as above disclosed.

The operation of this bottle capping machine will be clear from the foregoing but may be briefly summarized as follows:— Supposing the parts to be in the positions illustrated in Figs. 1 and 2, upon starting the motor 1, power will be transmitted from 70 its shaft 3 through the belt or chain 4 to the shaft 5, to the pulley 6, and by the belt 7 passing around said pulley 6, to the pulley 8. Now supposing the members of the clutch 75 10 to be engaged by moving the control 80 crank or handle 225 to its starting position, power will further be transmitted from the said pulley 8 through the said clutch 10 to the main or cam shaft 9.

The said shaft having keyed thereto as at 85 70 the clutch member 11, see Fig. 1, said clutch member together with its pivoted dogs 12 revolve with said shaft. Said dogs 12, as best illustrated in Fig. 6, are controlled by the adjustable spring 500, and 90 since the lever 13 takes against the lug 501, it follows that said lever cannot be released until a predetermined pressure overcomes the compression of said spring 500, all as will be clear from my said Patent #974402. 95 Therefore, the said lever 13 and pinion 15 will continue to revolve with said shaft 9 until this said predetermined pressure has been reached. The revolving of the pinion 15 pulls down the rack 17 associated 100 therewith, and the pulling down of said rack compresses the spring 22, see Fig. 2, while at the same time it pulls down the arm 23 and the capping head 25. Associated with the capping head 25 is a pin 71 adapted 105 to contact with each stud member 58 as it is brought thereunder.

A given stud member 58 being thus brought under the descending pin 71 the segment 56 corresponding to the stud member 58 in question is forced downwardly against the compression of its corresponding spring 60, and a bottle cap, not shown having been previously fed to the depression 57 of said member 56, the said cap is brought 110 115 into proper position above the top 72 of the bottle 100, and the capping head 25 continuing to descend with the rack 17, the said cap is crimped into the bottle head 72 in the manner substantially as described in my 120 said former Patent #1160084.

During the capping operation, a certain amount of pressure is brought upon the capping head 25, and is transmitted to the pinion 15 and the lever 13, and the dogs 12 125 and spring 500 are so adjusted as to cause said dogs to automatically trip or release the lever 13 of the clutch at each capping oper-

ation, thus permitting the parts through the action of spring 22 to return to their former positions.

If for any reason, however, the bottle 100 5 should be abnormally long or its head 72, be abnormally large, or if for any other reason, the said predetermined pressure on the lever 13 should be reached before the capping operation is completed, the said 10 lever will trip, whenever said pressure has been reached, and thus avoid breaking the bottle or a part of the machine.

In the meantime, the power shaft 9 in revolving turns the cam 30 and its cam 15 groove 31 causes a rotation of the flange 34, the tubular member 35, the tubular member 36 and with said tubular member 36 the parts 53, 42, 38, 43 and 45 together with the 20 depressible sectors 56 and pin 50 the spider 49 remaining fixed. In other words, after 25 the capping operation has been completed, the bottle is turned angularly about 45° and a new bottle and cap is brought into position underneath the capping head 25 whereupon the cycle of operations is repeated.

In this connection it will be noted that the 30 grooves 31 of the said cams 30 are pitched in opposite directions, as indicated by the dotted and full lines in Fig. 1, and therefore, they impart rotation in opposite directions to the standards 36 carrying the tables 38 and 110.

It sometimes happens that no bottle is in place underneath the capping head 25, and 35 in such event were no means provided, the pinion 15 would pull the rack 17 down beyond its normal distance with possible disastrous results to the machine. In order to provide against such a contingency, as 40 well as to insure that the lever 13 will trip with certainty, after each predetermined descent of the rack 17, I provide the cushioned stop 75, see Figs. 1 and 3, which may be made adjustable by means of the screw 45 threads 503, and which is adapted to receive the extreme lower end of the rack 17 whenever the said rack from any cause is lowered sufficiently to contact with the said stop 75.

50 The importance of the adjustable stops 75 will be appreciated when it is remembered that this machine in order to cap bottles of extreme lengths as well as very short bottles, will provide for a descent of 55 the rods 19 and 20, sufficient to accommodate both sets of bottles and that since the sectors 56, tables 38 and 110 and their associated parts are revolved at predetermined intervals, it is essential that the heads 25 and 60 65 shall descend and return to their former positions whether there are any bottles to be capped or not, and whether the bottles have broken or not, and therefore the provision of the stops 75 insure that the closure

will be tripped and the parts retained under all conditions. It is also of especial advantage in a machine of this nature that the cams 30 simultaneously rotate and also firmly hold the parts in their new positions and thus prevent the vibrations which ordinarily accompany prior machines and which vibrations serve to jolt the bottle caps out of position as well as the bottles, and thus cause the capping heads in their descent to crush the bottles. In this machine, on the other hand, the movement of the parts is so steady that there is no tendency at all for the bottles to become even slightly out of center, and therefore, the machine can be run with certainty of operation at a speed much higher than is ordinarily attained in prior machines.

The reference numeral 80 represents a ring or collar like member which surrounds the rigid extension 42, and said ring is provided with bottle holding fingers 81. Below said ring member 80 is a similar ring member 83 provided with bottle holding fingers 84.

It is obvious that those skilled in the art 90 may vary the details of the constructions as well as the arrangement of parts without departing from the spirit of the invention, and therefore, I do not wish to be limited to the above disclosure except as 95 may be required by the claim.

What I claim is:—

In an apparatus of the class described the combination of a power shaft; a yielding clutch adapted to normally transmit the 100 power of said shaft to cut off said power whenever the resistance exceeds a predetermined point; a reciprocating rod operated by said shaft; a reciprocating bottle capping head operated by said rod; pneumatic means to cushion the reciprocations of said rod and head; means comprising removable collars to readily change the points at which said head will begin its strokes to correspond with bottles of different heights; means comprising a positively rotatable table to support the bottles during the capping operation; adjustable means comprising a supporting disk contacting with said bottle supporting means to resist the strain brought on 110 the bottle supporting means during the capping operation; and adjustable means comprising a stop against which said rod may contact and adapted to trip said clutch and cut off the power of said shaft when said 120 rod has moved a predetermined distance, substantially as described.

In testimony whereof I affix my signature in presence of two witnesses.

THOMAS J. LEVEY.
